UNITED STATES PATENT OFFICE.

OTTO W. SCHAUM, OF PHILADELPHIA, PENNSYLVANIA, ASSIGNOR TO FLETCHER WORKS, INCORPORATED, OF PHILADELPHIA, PENNSYLVANIA, A CORPORATION OF PENNSYLVANIA.

SILVER-BURNISHING APPARATUS.

1,358,251.

Specification of Letters Patent. Patented Nov. 9, 1920.

Application filed May 26, 1917. Serial No. 171,279.

To all whom it may concern:

Be it known that I, OTTO W. SCHAUM, a citizen of the United States, and a resident of Philadelphia, county of Philadelphia, State of Pennsylvania, have invented certain new and useful Improvements in Silver-Burnishing Apparatus, of which the following is a specification.

The invention relates to apparatus for polishing silver utensils and it is particularly designed and constructed for performing the process shown, described and claimed in the Uebersax United States Patent No. 1,063,478, dated June 2, 1913.

15 The process which is performed in the apparatus that is the subject of the present application is clearly set forth in said Uebersax patent and further description thereof at the present time is deemed unnecessary.

20 An object of the present invention is to construct an apparatus with a plurality of drums for polishing silver articles of different sizes, that is with a relatively large drum wherein to polish relatively large pieces of silver, such as coffee-pots, platters or the like and a relatively small drum wherein to polish relatively small pieces of silver, such as knives, forks, spoons, salt-cellars, small ramekin dishes and the like.

25 A further object of the invention is to construct the polishing apparatus with a plurality of drums and to drive them in such a manner that either one or both of the drums can be operated as desired from a single source of power, such as from a continuously rotating common driving shaft.

30 As showing a specific embodiment of the invention reference is made to the drawings forming a part of this specification, in which drawings—

Figure 1 is a side view of a complete apparatus.

Fig. 2 is a longitudinal sectional view showing the gear construction at one end of the machine.

Fig. 3 is a transverse sectional view taken as on the plane indicated by the broken line 3—3 of Fig. 2 looking in the direction of the arrows.

40 Fig. 4 is a perspective view illustrating the arrangement of the drums relative to each other, showing the manner in which the drums are operated from the original source

of power, to wit, the driving pulley of the motor.

Fig. 5 shows the machine in plan.

Like parts are designated by the same reference characters in the specification and also on the drawings, and it will be understood that the parts shown in Fig. 4 are the same as the parts shown in the other figures, even though they are illustrated in Fig. 4 more or less diagrammatically.

The apparatus comprises a trough or trough construction 1 having legs 2 which may be considered as constituting a supporting frame for the trough. At one end of the trough, to wit, the left-hand end, there is located a relatively small drum 3 which is carried on a transversely extending drum shaft 4. This shaft is supported by any suitable bearing, as 5, on the trough. A larger drum 6 is carried on a longitudinally extending drum shaft 7. This shaft is supported by any suitable bearings, as 8 and 9, that are on or carried by the trough. At the right-hand end of the trough there is secured a casing 10 within which the major portion of the gear construction for driving the drums is located. Within this casing there is carried by bearings 11 and 12 a longitudinally extending common driving shaft 13. This shaft 13 has been referred to as the common driving shaft since it can continuously rotate and it is from this shaft that either one or both of the drums can be intermittently driven at will as will hereinafter appear.

This common driving shaft 13 has secured to it a worm-wheel 14 that is in mesh with a worm 15 located within the casing and which is upon the worm-shaft 16 that extends to the exterior of the casing. As this casing preferably contains lubricating material, such as oil or grease, it is made liquid-tight and the worm-shaft 16 extends through a packing 17 constructed so as to prevent the escape of the lubricating material. A thrust-bearing 18 is provided to take care of the thrust and wear resulting from the driving of the worm-wheel 14 by means of the worm 15. The worm-shaft 16 has secured to it a pulley 19 located on the exterior of the casing and this pulley is driven by a belt 20 from a pulley 21 driven by a motor 22 carried upon a bracket 23 secured to the trough 1 by 105 being connected to the supporting legs 2.

for the trough. The worm-shaft 16 may be referred to as a power-transmission shaft since this nomenclature serves as a convenient way of identifying a shaft that performs the function of transmitting power that it receives from the motor 12 on the one hand to either or both of the drums 3, 6 on the other hand, dependent upon whether clutches corresponding to the drums are closed and 10 which clutches are in a power-transmission train or gearing between said power-transmission shaft 16 on the one hand and the drums on the other hand. This motor 22 is located at the left-hand end of the trough 15 directly below the portion in which the drum 3 is located.

It will be noted that the common driving shaft 13 is continuously rotated from the motor while the apparatus is being used.

20 The bearing 9 for the longitudinally extending drum shaft 7 is, as a matter of fact, provided on the casing 10 and the shaft 7 extends through this bearing into the interior of the casing and to this extending 25 end of the shaft there is secured by means of a pin or key 24 a gear 25. This gear 25 is in mesh with a pinion 26 that is slidably mounted upon the common driving shaft 13. The casing 10 has a bracket 27 which provides a fulcrum at 28 for a lever 29 having a forked end 30 that engages a grooved portion 31 on the pinion 26. When the parts occupy the position shown in Fig. 2 a clutch member 32 on the pinion 26 engages a companion clutch 33 on the worm-wheel 14 and the gear or pinion 26 is held in this position by the lever 29, due to a locking mechanism 34 which is carried by the lever and which engages a notched portion 35 on the bracket 27. When the clutch members 32 and 33 engage each other the driving is from the worm-wheel 14 through the clutch members to the pinion 26, the gear 25 to the shaft 7 upon which it is carried and to 45 which there is secured the drum 6 whereby as the shaft 7 turns the drum 6 revolves therewith. The worm-wheel 14 may be considered as a part of the common driving shaft 13 when performing this function.

50 The construction just referred to may be considered as a reducing gear mechanism comprising a clutch between the common driving shaft 13 and the shaft 7 that carries and drives the drum 6.

55 The gearing construction between the shaft 13 and the shaft 7 constitutes means for positively transmitting power from the shaft 13 to shaft 7 when the clutch that is comprised in said power-transmitting means 60 is closed and hence said means may be referred to as a clutch-controlled, positive-power-transmitting means between the common driving shaft 13 and the large drum shaft 7.

65 The casing 10 also has a bearing 36 which

supports a transversely extending intermediate shaft 37. This intermediate shaft 37 has secured to it at its inner end a bevel-gear 38 which is driven by a bevel-gear 39 secured to the common driving shaft 13. A pulley 40 is secured to this shaft, which pulley is located on the exterior of the casing. A belt 41 passes from the pulley 40 to a pulley 42 which is revoluble relative to the transversely extending drum shaft 4, but 75 which can be coupled by means of a clutch 43 to said shaft to drive the latter. This clutch is under the control of the lever 44. The construction previously described may be referred to as a clutch-controlled power- 80 transmitting means between the common driving shaft 13 and the small drum shaft 4.

The construction described as a means for transmitting the power from the common 85 driving shaft to the transversely extending drum shaft 4 may also be broadly considered as a gearing comprising a clutch construction or as a belt and pulley construction comprising a clutch whereby the 90 shaft 4 and drum carried thereby can be rotated at will from the continuously rotating common driving shaft 13. This train of gearing—and it will be noted that a pulley and belt construction may be broadly 95 considered as gearing—is a reducing gearing but it does not reduce the speed as much as does the reducing gearing between the common driving shaft and the larger drum; in other words, the reducing gearing construction between the common shaft on the one hand and the drums on the other is such that the large drum makes a less number of revolutions per minute than does the small drum. 100

105 From the construction which has just been described it will be noted that by merely closing or opening the clutch 43 the small drum 3 can be rotated and stopped rotating at will while the common driving shaft 13 110 is being rotated and, as above pointed out, by closing and opening the clutch which comprises the members 32 and 33 the large drum can be rotated or stopped rotating, at will, while the common driving shaft 13 is 115 being rotated.

The trough 1 may be formed so as to include two compartments, or there may be only a common compartment into which both of the rotating drums extend. The 120 means for withdrawing any water or liquids from the trough is designated by 45. The drums are provided, as usual, with the main or body part 46 and a removable or cover part 47. As, however, the drums employed 125 may be of any suitable construction the details thereof are not herein described.

The improvements herein set forth are not limited to the precise construction and arrangement shown and described for they 130

may be embodied in various forms and modifications without departing from the spirit and scope of the invention.

What I claim and desire to secure by Letters Patent of the United States is:

1. An apparatus of the class described comprising in combination a trough into which there extends a drum mounted on a longitudinally extending drum shaft and a drum mounted upon a transversely extending drum shaft, a longitudinally extending common driving shaft, gearing between said common driving shaft and said longitudinally extending drum shaft, one gear of which gearing is slidably mounted upon one of said longitudinally extending shafts and has a clutch member for engaging a fixed clutch member secured to the shaft upon which the slideable gear is located, a bevel-gear carried on said common driving shaft, a transversely extending intermediate shaft carrying a bevel-gear in mesh with the first-mentioned bevel-gear, pulleys upon said transversely extending shafts, a belt for said pulleys, and a slideable clutch member on one of the transversely extending shafts for engaging a clutch member on one of said pulleys whereby when the clutch is closed said transversely extending drum shaft and drum thereupon will be rotated.
2. An apparatus of the class described comprising in combination a trough having thereupon a plurality of drums of different sizes, a common driving shaft, reducing gearing comprising a clutch between said common driving shaft and the larger drum, and a gearing comprising a clutch between the common driving shaft and the smaller drum, which last-mentioned gearing, when its clutch is closed, rotates the small drum at a higher speed than the larger drum is rotated by its gearing, when its corresponding clutch is closed, said gearing being constructed and arranged so that due to said clutches either one or both of the drums can be rotated or stopped while the common driving shaft is rotating, said gearing being constructed and arranged so that due to said clutches either one or both of the drums can be rotated or stopped while the common driving shaft is rotating.
3. An apparatus of the class described comprising in combination a trough having thereupon a plurality of drums of different sizes, a common driving shaft, reducing gearing between said common driving shaft and the larger drum, and a gearing between the common driving shaft and the smaller drum, the construction being such that either one or both of the drums can be rotated or stopped while the common driving shaft is rotating, the construction also being such that the smaller drum rotates at a higher speed than the larger drum when both of them are rotating.
4. An apparatus of the class described comprising in combination a main frame supporting a trough, a longitudinally extending drum shaft carrying a drum and which shaft is mounted in bearings on the trough, a transversely extending drum shaft carrying a drum which shaft is mounted in bearings on said trough, said trough having a gearing casing, a transversely extending worm-shaft carrying a worm which worm-shaft is mounted in bearings on said casing, a longitudinally extending common driving shaft mounted in bearings on said casing which common driving shaft carries a worm-wheel that is in mesh with said worm, a motor fixedly secured to the trough by being secured to the trough supporting means, a driving pulley on the motor, a driven pulley on the worm-shaft, belting passing over said pulleys, a pinion slidably mounted upon the common driving shaft which pinion has a clutch member that is movable into engagement with a clutch member on the worm-wheel, a gear secured to the longitudinally extending drum shaft and in mesh with said pinion, a lever for moving the pinion to and from clutch closing position, a bevel-gear carried by the common driving shaft, an intermediate shaft carried by said casing and having at one end a bevel-gear in mesh with the bevel-gear on the common driving shaft, a pulley secured to the transversely extending intermediate shaft, a pulley revolvably mounted on the transversely extending drum shaft, a clutch member slidably mounted upon said transversely extending drum shaft and arranged so that when in closed position it can lock said last-mentioned pulley to its shaft, means for moving the clutch to and from closed position, and a belt passing over the pulleys on the transversely extending drum therefor and the transversely extending intermediate shaft.
5. An apparatus of the class described comprising in combination a trough supporting a longitudinally extending drum shaft and a transversely extending drum shaft, there also being carried by said trough a casing in which there is located a longitudinally extending common driving shaft and a transversely extending intermediate shaft, a spur-gear on the common driving shaft meshing with a spur-gear on the longitudinally extending drum shaft one of said gears being connected to its shaft by a clutch construction, bevel-gearing between the common shaft and the intermediate shaft whereby the common shaft will drive the intermediate shaft, a pulley and belt construction whereby the intermediate shaft can drive the transversely extending drum shaft, there being a clutch construction located between the common driving shaft and the transversely extending drum shaft whereby

the latter can be driven from the common driving shaft at will.

6. An apparatus of the class described comprising in combination a longitudinally extending drum shaft, a transversely extending drum shaft, a longitudinally extending common shaft, a transversely extending worm-shaft, a worm and worm-wheel construction whereby the common shaft will be driven from the worm-shaft, gearing comprising a clutch construction between the common shaft and the longitudinally extending drum shaft, an intermediate shaft, gearing between said intermediate shaft and said common driving shaft whereby said intermediate shaft will be driven from said common driving shaft, and pulley and belt driving mechanism comprising a clutch construction whereby the transversely extending drum shaft can be driven from the intermediate shaft.

7. An apparatus of the class described comprising in combination a trough having at one end thereof a transversely extending drum shaft carrying a drum which extends into the trough, a longitudinally extending drum shaft carrying a drum which extends into said trough, a gear casing secured to the trough at the other end thereof, a longitudinally extending common driving shaft carried by said casing, a transversely extending intermediate shaft carried by said casing, a pulley on said intermediate shaft, a pulley on said transversely extending drum shaft, a belt for said pulleys, gearing between the intermediate shaft and the common driving shaft, and gearing between the common shaft and the longitudinally extending drum shaft, the apparatus being constructed so that by means of a clutch the drum on the longitudinally extending shaft can be rotated at will and so that the drum on the transversely extending drum shaft can be rotated at will.

8. An apparatus of the class described comprising in combination a trough having at one end thereof a motor, a drum and a transversely extending drum shaft therefor, at the other end a casing and between said drum and said casing a larger drum which larger drum is driven by a longitudinally extending shaft, said casing carrying a transversely extending worm-shaft which extends from the interior of the casing through a packing to the exterior of the casing, a pulley on the exterior portion of said shaft which pulley is driven by a belt from the motor, a transversely extending intermediate shaft carried by said casing and extending from the interior of the casing to the exterior thereof, gearing between the worm-shaft and the intermediate shaft for driving the latter, there also being gearing whereby the longitudinally

extending drum shaft is driven from the worm-shaft when a clutch is closed, pulleys on the transversely extending shafts and a belt therefor, the construction being such that the smaller drum at the end of the trough can be rotated at will.

9. An apparatus of the class described comprising in combination a trough having at one end thereof a drum mounted on a transversely extending shaft, a motor at the same end of the trough and secured thereto, a drum mounted on a longitudinally extending shaft, a casing secured to the trough at the other end thereof, a longitudinally extending common driving shaft carried by said casing, means between the motor and said shaft for continuously rotating said common driving shaft, spur-gearing between the common shaft and the longitudinally extending drum shaft, and a clutch whereby when the clutch is closed the drum on the longitudinally extending drum shaft may be rotated from the common driving shaft, an intermediate shaft carried by said casing and gearing between the intermediate shaft and the common driving shaft whereby said intermediate shaft will be continuously driven from the common driving shaft, a pulley and belt construction between said transversely extending intermediate shaft and said transversely extending drum shaft, and a clutch whereby the drum on the transversely extending shaft can be intermittently rotated at will.

10. A mechanism of the class described comprising in combination a casing having a transversely extending worm-shaft carried thereby which shaft extends to the exterior of the casing, a worm on the interior of said casing carried by said shaft, a longitudinally extending common driving shaft carried by said casing, a worm-wheel secured to said shaft which worm-wheel is in mesh with said worm, said casing having a bearing that receives the end of a longitudinally extending drum shaft, a spur-gear within said casing and secured to said drum shaft, a pinion slidably mounted on the common driving shaft, means carried by the casing for moving said pinion into and out of engagement with said worm-wheel which pinion and worm-wheel are constructed so as to form a clutch when in engagement with each other, and a transversely extending intermediate shaft carried by said casing and having a bevel-gear thereupon which is in mesh with a companion bevel-gear that is secured to the common driving shaft.

11. An apparatus comprising in combination a frame supporting a trough, a longitudinally extending drum shaft carrying a large drum, which shaft is mounted in bearings on the trough, a transversely extending drum shaft carrying a small drum which last-mentioned shaft is mounted in bearings

- on the trough, a motor located below the trough and under the small drum, a transversely extending power-transmission shaft, a belt drive between the shaft of the motor and the power-transmission shaft and of such construction that the power-transmission shaft revolves at a slower speed than the motor shaft, means comprising a clutch and a belt drive for transmitting power, 5 when the clutch is closed, from the transversely extending power-transmission shaft to the transversely extending drum shaft, the construction being such that the transversely extending drum shaft can remain at 10 rest while the power-transmission shaft is turning, when the clutch is opened, and so that said transversely extending drum shaft revolves at a slower speed than the transversely extending power-transmission shaft, 15 when the clutch is closed, and means comprising a clutch and positive gearing for transmitting power, when the clutch is closed, from the transversely extending power-transmission shaft to the longitudinally extending drum shaft, the construction also being such that the longitudinally extending drum shaft can remain at rest while the power-transmission shaft is turning, when said last-mentioned clutch is opened, 20 and so that the longitudinally extending drum shaft revolves at a higher speed than the transversely extending drum shaft when said clutches are closed.
12. An apparatus comprising in combination a longitudinally extending drum shaft carrying a large drum, a transversely extending drum shaft carrying a small drum, a motor located below the small drum, a transversely extending power transmission shaft, a belt drive between the shaft of the motor and the power-transmission shaft, means comprising a clutch and a belt drive for transmitting power, when the clutch is closed, from the transversely extending power-transmission shaft to the transversely extending drum shaft, the construction being such that the transversely extending drum shaft can be driven or can remain at rest while the power-transmission shaft is 30 turning when the clutch is respectively closed or opened, and means comprising a clutch and positive gearing including a worm driving a worm-gear for transmitting 35 power, when the clutch is closed, from the transversely extending power-transmission shaft to the longitudinally extending drum shaft, the construction being such that the longitudinally extending drum shaft can be driven or can remain at rest while the power-transmission shaft is turning when the clutch is respectively closed or opened.
13. An apparatus of the class described comprising in combination a frame supporting a trough, a longitudinally extending drum shaft carrying a drum, which shaft is mounted in bearings on the trough, a transversely extending worm-shaft, means between the transversely extending worm-shaft and the longitudinally extending drum shaft, which means comprises a worm associated with said worm-shaft and driven therefrom and a worm-wheel driven by the worm, said means also comprising a clutch which when closed permits power to be transmitted from the worm-shaft through the worm to the worm-wheel, thence to the longitudinally extending drum shaft and which clutch when opened permits the longitudinally extending drum shaft to remain at rest while the worm-shaft is turning, a motor secured in position in relation to the trough, a driving pulley on the motor, a driven pulley on the worm-shaft, belting passing over said pulleys, a second power transmission means between the transversely extending worm-shaft and the transversely extending drum shaft, which means comprises a pulley driven by power received from said worm-shaft, a pulley on said transversely extending drum shaft, and a belt that passes over said pulleys, said means also comprising a clutch which when closed causes the power to be transmitted from said worm-shaft to said transversely extending drum shaft, the clutches in said means being arranged so that either of the drums can be driven or can be stopped independent of whether the other drum is being driven or is at rest.

This specification signed and witnessed this 24th day of May, A. D. 1917.

OTTO W. SCHAUM.
